G.C. Haldorff

ATTORNEY.

UNITED STATES PATENT OFFICE.

LEE D. GIBSON, OF DALLAS, TEXAS.

LOCK COMBINATION.

Application filed December 21, 1925. Serial No. 76,764.

To all whom it may concern:

Be it known that I, LEE D. GIBSON, a citizen of the United States, residing at Dallas, in the county of Dallas and State of Texas, have invented certain new and useful Improvements in Lock Combinations, of which the following is a specification.

The present invention relates to improvements in locking devices and more particularly to a new and improved lock combination having for its chief object, to provide a combination difficult to alter or penetrate, and by which combination, the lock may be universally applied and used in locks of different character and scope.

In addition to the foregoing, the invention comprehends a counter plunger, co-acting with the locking element of the combination, which plunger materially increases the efficiency of the lock combination by preventing accidental release of the said locking element through excessive jar or otherwise.

The present application is proposed likewise as an improvement over the Letters Patent No. 1,566,473 granted the petitioner hereof on Dec. 22, 1925, for improvements in locks, bearing Serial Number 747,108.

With these and other objects and advantages in view, the invention consists in an improved arrangement of parts, by which the said objects are attained, and which will become apparent as the description proceeds, taken in connection with the accompanying drawings, wherein:

Figure 1 represents a diagrammatic plan view of the lock with its side removed, showing the relative position of locking elements.

Figure 2 is a detail view of the key, showing the peculiar shaped body thereof.

Figure 3 is a detail view in elevation, of the cylinder, spirally channelled to receive the key.

Figure 4 is a perspective view of the plunger housing.

Figure 5 is a perspective view in detail, of the plunger, and

Figure 6 is a perspective view of the lock, showing a reversed assembly of parts, with portions broken away, to more comprehensively illustrate.

Figure 7 is a further modified form of the combination, excluding the counter plunger.

In proceeding more in detail, attention is directed to Figure 1 of the drawings, wherein is illustrated a major housing 1, prefer-

ably divided into a series of compartments, to individually accommodate the different parts of the combination. This housing, although illustrated as being substantially rectangular in shape, may obviously be altered to correspond with the form and purpose of the lock in which it is desired to be used.

In the intermediate compartment 2 of the housing 1, the major locking plunger 3 is adapted to operate, while an adjacent compartment 4 contains the counter plunger 5, operating alternately with the said major plunger 3. Coinstantaneous alternating action of the two plungers is attained by reason of the pivoted lever 6, centrally mounted in the partition intermediate the compartments 2 and 4, and upon the ends of which rest the reduced lower ends of the plungers, as illustrated. The Figure 1 shows the plungers in normal locked position, while a compressive spring 5^a maintains this normal position.

Adjacent the central compartment on the opposite side, a third compartment 7 is provided, which contains a cylinder 8, having a spiral channel 9 therein, as shown more clearly in the detail view thereof in Figure 3. The cylinder rotates in either direction within the compartment.

The key, illustrated separately in Figure 2, is of spiral form also, whereby to be conformably received in the spiral channel 9 of the cylinder 8. The curvature of this spiral however, is not limited to any specific degree. The key 10 is provided as shown with a series of spaced fingers 11 on its sides, which are adapted, when the key is inserted into the spiral channel 9 of the cylinder, to protrude beyond the periphery of the cylinder, for purposes later described. The fingers 11 on the key are shown as being acute right angular projections, but it is obvious that a serrated key will function equally as well where a limited carriage of the plunger is desired.

The housing 12, illustrated in Figure 4, is provided with a plurality of slots 13, spaced to receive the fingers 11 of the key, when in its proper position within the cylinder 8 and rotated. Within this housing, the plunger 3 is adapted to slide, while the tops of the obliquely disposed slots 14 are adapted to coincide with the slots or apertures 13 of the housing.

Therefore, it is clearly obvious that, when each part is in its proper place within the

- major housing 1, insertion and rotation of the key 10, will cause the fingers 11 thereof to successively enter the slots 13 of the housing 12, and thence into the obliquely disposed slots 14 of the plunger, and riding along these slots, will cause the plunger 3 to move longitudinally of the housing 12, into or out of engagement with the keeper, not shown or described herein.
- 5 10 A modified example of the combination is illustrated in Figure 7, dispensing with the counter plunger 5, the spring 5^a acting directly upon the locking plunger 3. In this structure, the fingers 11 of the key 10 enter 15 first in the extreme upper apertures 13 of the wall between the cylinder 8 and the plunger, to engage within the oblique channels 14 of the said plunger, and which channels in this case, are required to be reversed 20 and directed toward the upper end of the plunger.
- While one form of combination is herein 25 illustrated, to show the principle involved in the invention, it should be understood that certain minor changes and modifications in form and application of the lock 30 may be resorted to, without departing from the spirit or intent of the invention as set forth in the appended claims:
- 30 1. A lock including a casing; a slotted cylinder disposed within the casing, a longitudinally movable plunger having spaced slots therein; a minor casing surrounding said plunger having apertures therein and 35 disposed adjacent said cylinder; a spiral key having fingers, the latter arranged to successively enter said apertures in the minor casing to engage successively within the spaced slots to actuate the plunger, 40 when the key is rotated.
2. A lock including a casing; a slotted cylinder disposed within said casing; a longitudinally movable plunger having spaced grooves therein; a minor casing surrounding 45 said plunger having apertures therein and disposed adjacent said cylinder; a spiral key having fingers: the latter arranged to successively enter said apertures in the minor casing to engage successively within said spaced grooves to actuate the plunger, 50 when the key is rotated.
3. In a lock; a partitioned casing, spaced apertures in one of said partitions; movable plungers in said casing, one of said plungers having spaced channels therein arranged to 55 coincide with the apertures of said partitioned casing; means to hold the latter plunger normally in locked position within the casing; a spirally channelled cylinder ad-
- 60 jacent said partitioned casing; a spirally formed serrated key receivable by said channelled cylinder whereby its serrations will successively enter said apertures and engage successively within said channels, when the key is rotated, actuating the 65 plunger.
4. In a lock, a casing provided with a series of compartments; a locking plunger and a spring controlled counter plunger arranged to alternately move within separate 70 compartments of said casing, the said first plunger having a series of spaced slots in its side; a compartment for said latter plunger having spaced apertures therein consecutively coinciding with said slots; a spirally channelled cylinder rotatably disposed adjacent said compartment; a twisted key having castellated edges receivable by 75 said cylinder, the projections of said castellated edges arranged to successively enter 80 the apertures of said plunger compartment, to ride within the slots of said plunger to cause the latter to move within the compartment when the key is rotated.
5. A lock combination including a pair of 85 alternating plungers, one of which is provided with spaced grooves, a housing with spaced apertures surrounding said latter plunger, said apertures consecutively coinciding with the grooves of the plunger; a spirally channelled cylinder adjacent said 90 housing; a spirally formed key receivable by said cylinder and having lugs spaced therein to successively enter the apertures of said housing to successively ride within the 95 grooves of the plunger to move the latter alternately with respect to its companion plunger, when the key is rotated, and means to resist the action of said plungers.
6. A lock combination including a pair of 100 alternating plungers, one of which is provided with spaced semicircular grooves, a housing having spaced apertures surrounding said latter plunger, its apertures arranged to successively correspond with the 105 said semicircular grooves; a spirally channelled cylinder disposed adjacent said housing; a spirally formed key receivable in the channel of said cylinder and having serrated edges, the serrations thereof arranged to 110 successively enter apertures of said housing to engage within the said semicircular grooves whereby to move the plunger with respect to said housing, when the key is rotated.
- 115 In testimony whereof I affix my signature.

LEE D. GIBSON.
